[57] CLAIM

The ornamental design for a vertical fastener for reinforcing rods, as shown and described.

DESCRIPTION

FIG. 1 is a front view of a reinforcing rod fastener in accordance with my invention;

FIG. 2 is a top view thereof;

FIG. 3 is a left side view thereof;

FIG. 4 is a bottom view thereof;

FIG. 5 is a right side view thereof;

FIG. 6 is a rear view thereof; and,

FIG. 7 is a perspective view thereof, the broken lines being shown for illustrative purposes only and forming no part of the claimed design.
